UNITED STATES PATENT OFFICE.

GEORGE E. LAMB, OF RANDOLPH, VERMONT.

ADDING-MACHINE.

1,233,066.

Specification of Letters Patent. Patented July 10, 1917.

Application filed September 27, 1913. Serial No. 792,155.

To all whom it may concern:

Be it known that I, GEORGE E. LAMB, a citizen of the United States, residing at Randolph, in the county of Orange and State of Vermont, have invented certain new and useful Improvements in Adding-Machines, of which the following is a specification, reference being had therein to the accompanying drawing.

The general object of this invention is to provide a rapid and convenient pocket adding machine such that correct sums must necessarily be registered when the machine is properly operated unless parts of the mechanism be broken, and such that, without making parts too small or delicate for practical service, the whole may have approximately the size and appearance of a watch. With this object in view, means are provided for adding columns in succession beginning with the highest or the lowest, for having the apparatus operated by a main spring to register the proper amount when parts corresponding to the figures to be added are momentarily pressed, for locking the parts against accidental movement affecting the amount registered; for winding the main spring by rotating the stem, and for resetting at zero, these being desirable and for the most part well known results, which, however, I obtain by construction involving novelty.

In the drawings,

Figure 1 is a face view of the apparatus when inclosed in a suitable case.

Fig. 2 is an enlarged similar view, the case and a dial plate being omitted and some other parts being broken away.

Fig. 3 shows a section on the line 3—3,

Fig. 5.

Fig. 4 is a section on the line 4—4, Fig. 2.

Fig. 5 is a section on the line 5—5, Fig. 2.

Fig. 6 is a detail view of registering and resetting devices.

Fig. 7 shows a section on the line 7—7,

Fig. 6.

Fig. 8 shows a section on the curved line 8—8, Fig. 6.

Fig. 9 is a detached, detail, diametrical section showing parts of registering and resetting devices.

Fig. 10 is a section parallel to and just below a gear 54, Fig. 4.

Fig. 11 is a perspective view of pawl devices of Fig. 10.

Fig. 12 is a section on the line 12—12.
Fig. 10.

Fig. 13 is a section on the line 13—13,
Fig. 2.

Fig. 14 is a detail of winding devices, 60 looking toward the left in Fig. 13.

In general, the apparatus involves a central, normally pawl-locked main gear which is urged to rotate by a mainspring, a series of distinct similar registering devices along- 65 side the plane of the main gear, within the line of its periphery, and equidistant from its axis, two pinions fixed to the same shaft, the first engaging the main gear at all times and both movable about that gear to bring 70 the second into engagement with any one of the registering mechanisms; sliding pins corresponding, respectively to the nine digits; means whereby pushing any of the pins unlocks the main gear and at the same 75 time projects the pin into the path of a stop limiting the rotation of the gear differently according as one or another of the nine pins is pushed, whereby the main gear and said second gear, with the particular regis- 80 tering mechanism with which it may for the time being engage are rotated to a greater or less extent.

It also involves means, actuated by man- 85 ual rotation of a stem, for moving said first and second pinions circumferentially around the main gear from the units adding mech- anism to similar mechanisms for adding higher orders and at the same time wind- 90 ing a spring for urging return movement. 90 It also involves manually operated means whereby the spring last mentioned is allowed to cause such return movement, step by step; also means whereby all the registering mechanisms may at will be re- 95 stored to initial zero indication; also for winding the mainspring; and also for lock- ing against accidental change of indication. Still further, the construction is such that the different orders of numbers may be add- 100 ed in any desired sequence.

In these views, 1 represents the casing in substantially the form of a watch case. This case contains a main frame made up of parallel circular plates 2, 3, 4, rigidly connected by posts 5 and supporting most of the working parts. Above or in front of the plate 4 is fixed a disk 6, Fig. 1, perforated at 7 to show registry numerals and at 8 to permit the insertion of a pencil or the 110

like to actuate the mechanism for adding the numbers designated by numerals alongside the apertures, respectively. Near each opening 7 is a small perforation 9 to be 5 automatically covered and uncovered by a white area at z , Fig. 2 upon a member 36, thus indicating to the eye when the apparatus is set for adding a particular column, whether units, tens, hundreds, etc. 10 represents a mainspring barrel having peripheral teeth 11 rotatable about a shaft 12, and containing a mainspring 13, which drives a gear 14, pinion 15, gear 16, and pinion 17 fixed to the shaft 12, which carries above 15 the frame plate 3 a main gear 18, engaging a pinion 19 Figs. 3 and 5 for driving registering devices to be described. The gear 18 is normally held against rotation by a pawl 20 (Fig. 3) pivoted at a on the frame plate 3. Above the gear 18 is revolubly mounted upon the same shaft a peripherally geared segment 21 of slightly smaller radius than the gear and having teeth adapted to register with those of the gear, and above the sector 25 and fixed thereto is a thin sector-like plate 22 (for convenience in manufacture made as a separate piece) of greater radius. One side of this plate is stepped and provided with circularly cut, open slots 23 the inner 30 end walls of the slots and intermediate portions of the plate being at progressively increasing distance from the radius extending from the axis of the shaft to the outer limit of the stepped margin of the plate. Above 35 the sector plate a block 24 is fixed to the frame plate 4 (Fig. 13), and in said plate and block are mounted two rows of vertical pins 25 corresponding to the apertures 8 (Fig. 1). Each pin is provided, below the 40 plate 4, with a conical enlargement 26 and is normally held in its uppermost position, above the plate 22, by a spring 27 and with its cone above a radial pawl-retracting slide 28 normally held in the position shown in 45 Fig. 2 by a spring 29 acting on an arm 30 of the slide. The slide 28 is cut away to form elongated openings near the ends of which respectively, the pins 25 pass through the plate, as seen in Figs. 2 and 5.

50 When any pin is depressed its lower end passes into the plane of the plate 22 opposite one of the curved recesses above mentioned or, according as the pin depressed is in one or the other of the two rows, opposite 55 the edge of a portion of the plate between consecutive recesses; and at the same time the cone on the same pin pushes the slide 28 radially outward. The outer end of this slide being connected to the pawl 20 by an 60 arm or link 31 (Figs. 3, 5), this swings the pawl out of engagement and at the same time throws into engagement with both 18 and 21 a thick or double pinion 32 mounted on the opposite arm of the pawl. The gear 18 being free it is suddenly rotated by the

mainspring, and since the pinion 32 engages the teeth of both this gear and the segment 21, the latter rotates to exactly the same extent carrying the plate 22 forward until its stepped margin strikes the depressed pin 70 and arrests the rotation. The angular extent of this rotation corresponds to the number of units in the number (Fig. 1) alongside the pin which was depressed.

The instant the depressed pin is released, 75 it rises, the slide moves inward, the pawl engages the gear 18, the pinion 32 moves out of engagement, and a spring 33 restores the segment 21 and plate 22 to initial position resting against a stop c .

All this is repeated as often as any pin is depressed.

Each momentary rotary movement of the gear 18 actuates registering mechanism (for convenience mounted on a subordinate 85 framework y carried by the main frame) through its engagement with the pinion 19, mounted upon and rotating a shaft 34 which bears also a rigidly connected pinion 35 and is mounted in a frame 36 swinging about 90 the central shaft 12, to bring this pinion into engagement with one or another of a series of equal pinions 37 fixed upon the shafts 38, respectively, of common rotary disks 39 fast upon their shafts and bearing 95 the digits in position to be exposed at the apertures 7, Fig. 1. Each shaft 38 carries an additional equal fast pinion 40, from which a tooth, corresponding to the character 0 on the disk 39 is removed, a projecting fast finger 41, between the gears 37, 40, and a fast finger 42 above the latter gear. As the shaft 38 is rotated by the main gear 18, the finger 41, acting through a gear 43, at the completion of each revolution rotates 100 the gear 37, of the next higher disk 39, one step. The units gear 37 is yieldingly held to prevent accidental movement, by a pawl 44 (Fig. 6) and normally all the gears 43 are similarly held by stops 45 carried by 105 sliding members 46 and normally held in engagement by springs 47. The member 46 has an arm 48, the end of which normally lies in the path of the finger 42 and in such position that the latter pushes the member 110 inward so that the stop 45 releases the gear 43 while the latter is acted upon by the finger 41. It follows from the described construction that when the frame 36 is so turned as to engage the gear 35 with any pinion 37, 115 rotation of the main gear 18 will rotate that pinion 37 and its disk 39 without affecting any disk of a lower order but advancing the disk of the next higher order 120 one step at the completion of each revolution of the gear 37. Each pinion 37, 40 has, of course, the usual ten tooth spaces 125 registering with the ten characters on the corresponding disk 39.

For re-setting all the disks to zero, a 130

geared segment 48', Fig. 6, in the plane of the pinions 40, is pivoted to bell cranks 49 pivoted in the frame 36 and connected by a link 50 in such manner that when the arm 5 of one bell crank is moved in the proper direction, by swinging the segment until the arm meets the stop x , Fig. 2, the segment is carried inward into position for engaging the pinions. If the frame 36 be now swung 10 from one limit to the other of its path, curved bar 52 fixed to 48' pushes the members 46 inward releasing the pinions 40 in succession, and the segment rotates all in succession bringing the zero of each disk 15 39 to its aperture 7, Fig. 1, in which position it remains because the removal of the zero tooth of each pinion leaves at this point nothing to be affected by the teeth of the geared segment. The re-setting being completed 20 the geared segment is automatically moved out of action by reverse movement of the bell crank arm, caused by a stop x' , Fig. 2, and a suitable spring 51 gently resists its movement from inner or outer position. To 25 insure accuracy in the position of the geared segment when moved inward, for resetting the long circularly curved bar 52 is fixed to the plate in position to slide in contact with the outer ends of several of the slides 46 at 30 the same time; and, for adding the bar being in outward position, a rounded stop d , Figs. 6 and 7, pushes the slides inward, separately, as they are separately brought to adding position, thereby unlocking each pinion 43 35 while the next pinion 37 to the left is being rotated by the pinion 35.

For swinging the frame 36 back and forth, a gear 53 is fixed to its axial hub (Fig. 9) and this engages a gear 54 (Figs. 40 3, 4) which is at will manually rotated clockwise by the stem 55, projecting from the casing, and acting through a bevel gear 56, bevel and spur pinion 57, rigidly connected (or very thick) pinions 58 which at 45 proper times mesh with the gear 54. The pinions 58 are mounted on a bar 59 pivoted centrally to swing about the axis of the pinion 57 and so swung by a push pin 60 acting against the resistance of a spring 61, to dis- 50 engage the pinion 58 and throw a gear 62, mounted on the opposite end portion of the bar 59 into engagement with the mainspring barrel gear for winding the mainspring by rotation of the stem 55. The gear 62 is 55 made in two ratchet connected parts, as in watch-winding devices, so as to permit alternate forward and backward rotation of the stem. Tension put upon the mainspring is retained by the spring pawl 63, Fig. 3.

60 Below the gear 54, Figs. 3, 10, 11, 12, a pawl 64 is pivotally mounted upon a bracket of the middle main-frame plate to swing about a center 65 into and out of the path of equally spaced pins 66 depending in a circle from the gear 54 which transmits mo-

tion to the frame 36 as has been shown, and which, through the action of a spring 67', Fig. 3, normally holds that frame in position for actuating the units pinion of the registering devices. The pawl is normally held out of the path of the pins by a spring 67, one of the pins however being normally engaged by a second holding pawl 68 yielding urged into engagement by a spring 69. The pawl 64 is thrown into the path of the pins and the pawl 68 withdrawn therefrom by a push bar 70 actuated by an axial sliding rod 71 in the stem 55 and normally held retracted by a spring 72, and when this movement of the pawls occurs the gear is at 75 once rotated by its spring until one of the pins strikes and is arrested by the pawl 64. Cessation of pressure on the push rod allows the springs to restore both pawls to normal positions, with the pawl 68 engaging the pin 80 next succeeding that before held. The net result, then, of pressing the push rod 70 is to rotate the gear 54 one step, with corresponding angular movement of the frame 36, this step being just enough to move the 85 pinion 19 from one pinion 37 to the next, that is from one order of numbers to the next. The pawl 68 is so formed that while it normally holds the gear against rotation it permits the pins to escape when the gear 90 is forcibly rotated by the pinion 58. While substantially the same mechanism may provide for adding either units or higher orders first, in the particular embodiment illustrated, if it be desired to add higher orders 95 first the gear 54 is manually rotated clockwise by the pinion 58 to carry the frame 36 to the left-hand limit of its path, and is returned step by step by the spring 67' when the pawls 64, 68 are repeatedly operated in 100 the manner already described, by pressing the pin 71. Thus the adding mechanism is moved from units adding position by manual rotation of the stem, the movement always increasing the tension of the spring 105 67', and is returned, step by step, by that spring when pressure upon the pin 71 repeatedly actuates the pawls which hold the gear 54 against rotation.

What I claim is:

1. The combination with similar registering mechanisms for each order of numbers, of spring-driven means for actuating any one of said mechanisms, a rotary stem for winding the spring, devices for moving said means into and out of operative connection with any one of said mechanisms, and means for at will applying the rotary power of the stem to winding or to the actuation of said devices.

2. The combination with distinct registering mechanisms for the orders of numbers, respectively, arranged in a plane equidistant from a central axis, of spring-driven means adapted to be moved into operating

115

120

125

130

engagement with any of said mechanisms, devices for manually moving said means in one direction from mechanism to mechanism, spring-actuated devices for moving 5 said means in the contrary direction from one mechanism to the next, and manually operated means for releasing the spring-actuated devices, to allow such movement.

3. The combination with registering devices, of a normally locked spring-actuated gear for driving said devices, a segment independently revolute about the gear's axis and having teeth registering with the gear teeth, a pinion adapted to engage the teeth 10 of both gear and segment simultaneously, compelling identical rotation, means for simultaneously unlocking the gear, momentarily, and throwing the pinion into engagement, means for arresting the rotation at a 15 predetermined point, and means for restoring the segment to initial position when the gear is relocked.

4. The combination with a series of distinct registering devices, for the different orders of numbers, equidistant from a central axis, of a normally inactive actuating device more distant from said axis, mounted to swing bodily about said axis into operative connection, successively, with said devices, means for thus swinging said device and holding it temporarily, means for causing it to become active while so held, and spring actuated means for swinging said device in a contrary direction.

35. 5. The combination with a series of distinct registering mechanisms having like mutilated pinions circularly arranged about a fixed axis, of a member swinging through a limited path about the same axis, a rack, 40 mounted upon said member to move into and out of position for engaging said pinions as the member swings, and means whereby said rack is oppositely shifted as said member reaches the limits of its movement.

45. 6. The combination with a spring-driven gear and registering mechanisms operable therefrom, of a geared sector of slightly smaller radius than said gear mounted near

the same for limited rotation about the same axis, a pinion movable into and out of engagement with both the gear and segment to lock them together, pins movable into and out of position for meeting stops upon said sector at various angular distances from the initial position of the sector, manually operable means for at will disengaging said pinion and locking said gear leaving the sector free, and a spring for restoring said sector to initial position when freed by the pinion.

7. The combination with a spring-rotated, normally locked, gear, of a series of similar geared registering devices equidistant from the axis of the gear, a pinion carrying frame swinging about said axis to bring its pinion 65 into engagement with the registering devices in turn, automatic means for unlocking the proper registering devices and locking all others when said pinion is in position to actuate any one of them, a curved rack 70 mounted on the said frame, means for at will moving the rack inward to position for actuating the several registering devices, for resetting all at zero, means for automatically holding the rack in its inward and 75 outward positions, and automatic means for moving the rack outward when the resetting swing of the frame is completed.

8. The combination with a casing of a rotary stem shaft, a driving gear within the 80 casing, a spring actuating the driving gear and wound by said shaft, a series of spaced geared registering devices equidistant from the axis of said gear, a frame mounted for limited angular movement about the axis of 85 the gear, a pinion carried by the frame for engaging each registering device in turn, a resetting rack carried by the frame, and means whereby the frame may be moved back and forth within its limits.

In testimony whereof I affix my signature in presence of two witnesses.

GEORGE E. LAMB.
